NOZZLE ADAPTER FOR A HYDROTHERAPY UNIT

Samuel F. Peterson, Jr., Chicago, Ill., assignor to
Associated Mills, Inc., Chicago, Ill.

Filed June 17, 1974, Ser. No. 479,594

Term of patent 14 years

Int. Cl. D24—04

U.S. Cl. D83—1 C

FIG. 1.

FIG. 2.

FIG. 3.

FIG. 4.

FIG. 1 is a top plan view of an adapter showing my new design.

FIG. 2 is an elevational view taken from one side thereof, the opposite side being a mirror image of the side shown.

FIG. 3 is an elevational view taken from one end thereof.

FIG. 4 is an elevational view taken from the end opposite that shown in FIG. 3.

I claim:

The ornamental design of a nozzle adapter for a hydrotherapy unit, as shown and described.
